OPERATING MECHANISM FOR DOORS

James A. Youngblood, Dallas, Tex.

Application August 12, 1935, Serial No. 35,835

15 Claims. (Cl. 189—7)

This invention relates to new and useful improvements in operating mechanism for doors.

One object of the invention is to provide an improved mechanism which is particularly adapted for use with the doors of jail cells which are ordinarily located in a long row or block, the mechanism being so constructed that the operator may open, close, lock or unlock any number or all of the doors from a single point.

10 An important object of the invention is to provide an improved operating mechanism for jail doors which is so arranged that any number or all of the doors may be locked or unlocked in an open or closed position and also whereby any 15 number or all of the doors may be moved to an open or closed position, the mechanism including a minimum number of parts whereby the device is not only efficient in operation but is also simpler and cheaper to manufacture as compared with similar devices now in general use.

20 Another object of the invention is to provide an improved operating mechanism for jail doors including a door operating unit and a door locking unit, there being a co-action between the units 25 whereby the locking unit cannot be actuated until and unless the door or doors have moved to a completely open or a completely closed position, or the doors cannot be moved until after the locking unit has been actuated to unlock the doors, 30 which eliminates danger of jamming the locking mechanism as would be the case if the same were operated while the door or doors were in motion.

A further object of the invention is to provide 35 an improved operating mechanism for a plurality of jail doors including a door operating unit and a door locking unit, the first named unit serving to open or close all of the doors simultaneously while the latter unit serves to lock or unlock all of the doors simultaneously, and a single means for 40 each door arranged to co-act with both the door operating unit and the locking unit for preventing that door from being locked, unlocked, opened or closed, as the case may be, upon the next actuation of the two units.

45 Still another object of the invention is to provide an improved operating mechanism for a plurality of jail doors including means attached to each door and arranged to move therewith for indicating to the operator, who cannot view all 50 of the doors, the particular position of each door during its movement from or to an open or closed position, whereby said operator is at all times informed which doors, if any, are not operating correctly.

55 A still further object of the invention is to pro-

vide an improved operating mechanism for locking, unlocking, opening or closing a plurality of jail doors which are located in a row, said mechanism including a single means for each door for cutting out said door whereby it becomes inoperative, the actuation of said cut out means being accomplished through pull rods which extend from each means to a central operating point, said cut out means being so arranged and mounted that the pull rods for operating the same may be 10 mounted in various vertical planes which eliminates the necessity of bending said rods, thereby making for more efficient operation of the mechanism.

15 A still further object of the invention is to provide an improved operating mechanism for jail doors, whereby all the operating levers for locking, unlocking, opening or closing the doors, or for cutting out any number, or all of said doors to make them inoperative, is mounted at a single point, whereby one operator can easily control all 20 the doors.

25 A construction designed to carry out the invention will be hereinafter described, together with other features of the invention.

The invention will be more readily understood from a reading of the following specification and by reference to the accompanying drawings, in which an example of the invention is shown, and wherein:

30 Figure 1 is an elevation of a pair of jail cells which form a part of the usual row of cells and showing only the essential elements of the door operating mechanism, constructed in accordance with the invention, one of the cell doors being open while the other is closed.

35 Figure 2 is a transverse, vertical sectional view taken through one end of the casing for the operating mechanism and showing only the manual controls and actuating members for the locking and door operating bars.

40 Figure 3 is a horizontal, cross-sectional view, taken on the line 3—3 of Figure 2.

45 Figure 4 is a transverse, vertical, sectional view, taken on the line 4—4 of Figure 2.

Figure 5 is a view, with the casing in section, of the complete operating mechanism for one door.

50 Figure 6 is a horizontal, cross-sectional view, taken on the line 6—6 of Figure 5.

55 Figure 7 is an isometric view of the locking and door operating bar with the associated parts for one door.

Figure 8 is an elevation of the same showing the casing in section,

Figure 9 is an isometric view of the cut-out member,

Figure 10 is an enlarged view, showing the actuating member for the vertical latch bar,

5 Figure 11 is an isometric view of the same,

Figure 12 is a transverse, vertical, sectional view, taken on the line 12-12 of Figure 6,

Figure 13 is a transverse, vertical, sectional view, taken on the line 13—13 of Figure 6.

10 Figure 14 is an enlarged view showing the cut-out member, and actuating member for the latch bar,

Figure 15 is a horizontal, cross-sectional view, taken on the line 15-15 of Figure 12, and

15 Figure 16 is an isometric view of the latch bar, showing the door in section.

In the drawings, the numeral 10 designates jail cells which are usually mounted in rows or blocks along a single corridor. It is noted that only two cells are shown, but it is pointed out that any desired number may be disposed in a single row. The cells are of the ordinary construction employed in the usual steel jail system and each cell is provided with a sliding door 11. Each door is formed with an upwardly extending extension member 11' which passes through a slot 12 in the casing 32 which encloses the mechanism and which extends longitudinally over the row of cells. This extension has suitable rollers 13 journaled on its rear side on pins 14, and these rollers are arranged to ride on a longitudinal track 15 (Figures 12 and 13), whereby the door is suspended from said rollers. It is noted that the track 15 is of sufficient length so that the door may slide to a completely open position without said rollers riding off of the track. This construction is generally practiced in the construction of jail cells, and a more detailed description is deemed unnecessary.

40 From the above, it will be seen that each cell door is suitably mounted to slide, whereby the doors of the cell may be easily opened or closed. For locking each door in its opened or closed position, a vertically movable latch bar 16 is provided. The latch bar is preferably angular in cross-section (Figures 12, 14, and 15), and is slidable within a vertical casing or housing 17. The casing, of course, protects said latch bar from being tampered with by the occupant of the cell.

45

50

The outwardly extending leg 16' of the latch bar is terminated short of the lower end of said bar. This leg is arranged to engage notches 18 which are formed in a flange 19 which extends upwardly from the supporting base member 20 of the door 11. The notches 18 in this flange are so located that when the door is in a completely closed position and the latch bar 16 is lowered the lower end of the leg 16' of said latch bar will engage one of the notches. At the same time that the lower end of the leg 16' enters one of the notches 18, the upper end of said latch bar moves into a notch 21 which is formed in the upper frame member 20' of the door 11. It will be seen by observing Figure 12 that with the latch bar 16 in a lowered position the door is incapable of movement. When the latch bar is raised the lower end of its leg 16' moves out of the notch 18 in the lower supporting frame bar 20 of the door 11. At the same time the upper end of said latch bar moves out of the notch 21 in the upper member 20' of the door 11, and a slot 23 which is cut in the leg 16' of the latch bar moves into alignment with said upper member 20', whereby the inner edge of said upper frame member may

travel through said slot to permit movement of the door. From the above, it is obvious that with the latch bar in a lowered position the door 11 is locked against movement. When the latch bar 16 is raised said door may be moved to an open position. For locking the door in an open position similar slots 21' and 18' are formed in the other end of the frame members 20 and 20' of said door, whereby when the door is moved to an open position the latch bar may be lowered so that its leg 16' will engage the notches 18' and 21' to lock said door in an open position. 10

It is noted that a latch bar is provided for the door of each cell 10. For actuating the latch bar 16 to raise and lower the same, said latch bar has its upper end extending through a slot 24 in the bottom 25 of the casing 32. This upper end of the latch bar 16 is pivotally connected to an actuating member 26. The actuating member comprises two triangular shaped plates 27 which are disposed one on each side of the latch bar, whereby a pin 28 may be passed through the plates and bar to provide a pivotal mounting. The plates 27 are suitably pivoted on a pin 29 which is supported in bearing plates 30 which extend upwardly from the bottom 25 of the casing. As clearly shown in Figures 10, 11, and 14, the actuating member 26 acts as a bell crank lever and when the latch bar is in a lowered position the pin 28 and the pivot 29 of said actuating member 26 are in horizontal alignment with each other. It will be obvious that when the plates 27 are swung, or in other words when the upper end of the actuating member 26 is swung the latch bar 16 will be lifted. Therefore, the raising and lowering of the latch bar is accomplished through the medium of the pivoted actuating member 26.

For imparting a swinging movement to the actuating member 26, so as to operate the latch bar 16, an elongated locking bar 31 is provided. This locking bar extends the entire length of the row of cells and is capable of a longitudinal movement. The bar 31 provides a master operating means for actuating all of the latch bars in a particular row of cells. The latch bar actuating member 26 together with the longitudinally movable locking bar 31 are enclosed in an elongated casing 32 which is mounted adjacent the top of cell doors, and extends the entire length of the row of cells. This casing may be constructed of any suitable metal and is for the purpose of protecting the operating mechanism from damage by the cell occupant. If desired, the casing 32 may be provided with a suitable access panel 33 above each cell door, whereby ready access may be had to the operating mechanism for that particular door.

As clearly shown in Figures 2, 4, 6, and 7 the locking bar 31 extends through the end wall 32' of the casing 32, and the extreme outer end of this bar extends into a control compartment 34 which is located at one end of the row of cells, adjacent the end cell in that row. The control compartment has all the manually operated members therein, as will be explained. The extended end of the locking bar 31 has the upper end of an actuating lever 35 pivoted thereto. The lever 35 is pivoted near its upper end on a pin 36 which is supported in a suitable ear or bracket 37 which extends outwardly from the rear wall of the control compartment 34. The lower end of the lever is provided with a suitable handle 38 which is slidable through guide gears 39 extending outwardly from the inner wall of said com- 75

partment 34 (Figure 2). It will be obvious that when the lower end of the lever 35 is swung inwardly, the upper end of said lever will be moved outwardly toward the outer portion of the compartment 34. This movement of the upper end of the lever will move the locking bar 31 in a direction to the left (Figures 2, 3, and 10).

For detachably connecting the locking bar 31 with the actuating member 26 of the latch bar 16, a yoke 40 has one end pivoted to the upper end of the actuating member 26. The locking bar 31 passes between the plates 27 of the actuating member and also between the arms of said yoke 40. The other end of the yoke has its arms connected by a transverse pin 41, the pin being arranged to engage in a slot 42 formed in the upper edge of the locking bar. It is obvious that with the pin 41 located within the slot or notch 42 within the bar 31, that the movement of said bar to the left (Figure 10) will impart a swinging movement, as shown in dotted lines in Figure 10, to the actuating member 26. Such swinging movement of the actuating member 26 will, of course, raise the pin 28 in the outer end of 20 said member, whereby the latch bar 16 is raised so that its leg 16' will disengage the notches in the supporting bars 20 and 20' of the cell door 11, whereby the door is unlocked and may be slid to an open position. If, after the door is 30 swung to its open position it is desired to lock said door in such position, it is only necessary to swing the lever 35 back to its original position which will move the locking bar 31 to the right in Figure 10 which will swing the actuating member 26 back to its original position through the medium of the yoke 40 and pin 41, whereby the latch bar 16 is lowered to engage the notches 18' and 21' to lock the door in its open position.

So long as the yoke 40 of each actuating member 26 for each particular latch bar 16 of the various doors is engaging in its notch 42 of the locking bar 31, it will be obvious that a swinging of the lever 35 will operate the latch bars of all of the doors in unison and simultaneously. In other words, a swinging of the operating lever 35 will unlock all the doors at the same time. Similarly, it will lock all the doors at the same time. Therefore, it will be seen that a single control means is provided for actuating the lock 50 of all of the doors of the cells in a particular row. It is obvious that if the pin 41 of any one of the yokes 40 which control a particular latch bar is disengaged from its notch 42 of the locking bar, then the actuation of said locking bar 31 will not operate the actuating member 26 of the particular latch bar. However it will operate the latch bars of the other doors which are connected thereto through the medium of the yoke 40. Thus it will be seen that any particular door may remain in a locked position, open or closed, while the other doors are being unlocked, opened and relocked, as will be explained. For imparting motion to the sliding doors 11 to open or close the same, the extension 11' which extends upwardly from each door through the slot 12 in the bottom 25 of the casing has a pair of plates 45 suitably secured to either side thereof. These plates are preferably rectangular in shape and may be welded, riveted or otherwise secured to the extension 11'. As clearly shown in Figures 7 and 13, an elongated actuating or door propelling bar 46 extends within the casing 32 throughout the entire length thereof. This 70 actuating bar is in vertical alignment with the

extension 11' whereby said bar passes between the upper ends of the plates 45 which are carried by said extension. This propelling bar is arranged to move longitudinally within the casing, as will be explained. 5

For connecting the plates 45 and extension 11' with the movable actuating bar 46 a pair of yokes 47 and 48 are provided. The yoke 47 extends outwardly from one end of the plates 45, being pivoted thereto and has its outer end connected by a transverse pin 47' which is arranged to engage in a notch 49 formed in the upper edge of the actuating bar 46. The second yoke 48 extends from the other end of the plates 45 being pivoted thereto, and has the outer end of its 15 arms connected by a transverse pin 50 which is arranged to engage a similar notch 51 formed in the upper edge of said bar 46. It is noted that the notches 49 and 51 are formed so as to have one side substantially at right angles to the upper 20 edge of the bar 46 while the other side is inclined as is clearly shown in Figure 7. It will be obvious that when the pins 47' and 50 of the yokes 47 and 48 respectively are engaging in their notches 49 and 51 that a movement of the bar 25 46 in either direction will cause the plates 45, extension 11' and the door 11 to be moved in that direction.

Assuming that the door is in a closed position (Figures 7 and 8) with the yokes 47 and 48 connected with the actuating bar 46 through the medium of the pins and notches, it will be obvious that when the actuating bar is moved to the right in Figure 8 that the flat side of the notch 51 engaging the pin 50 of the yoke 48 will pull the door along with the bar. Thus the extension 11 is caused to travel through the slot 12 provided in the bottom 25 of the casing, and the door 11 is moved to its open position, as shown in dotted lines in Figure 8. After the door has been moved to this position, it will be obvious that a reverse movement, or a movement to the left in Figure 8 of the actuating bar 46 will cause the flat side of the notch 49 to engage the pin 47' of the yoke 47 to cause the plates 45 and extension 11' to be 40 carried to the left with the movement of said actuating bar. Thus the door will be moved back to its closed position. It is noted that the yoke 48 and its connection with the notch 51 of the actuating bar 46 serve to move the door to an 45 open position when the actuating bar 46 is moved to the right in Figure 8. When the actuating bar is moved to the left the other yoke 47 serves to return the door to its closed position. It is, 50 of course, obvious that any number of doors may be connected in this manner to the actuating bar 46 whereby any desired number of doors may be 55 opened or closed by a single actuation of said bar.

Assuming that there are a plurality of doors connected with said bar through the medium of the yokes 47 and 48, and further assuming that the doors are all in a closed position, it will be obvious that so long as the yokes 48 are connected with the actuating bar 46 that all of the doors will be opened when said bar is actuated or moved to the right, Figure 8. However to disconnect any one of the doors and permit it to remain in a closed position while the others are moved to an open position it is only necessary to 60 disengage the pin 50 of the yoke 48 from its notch 51 in the actuating bar. When this is done it will be obvious that movement of said bar will not open that particular door because there is no connection between said bar and the door. When 65 70 75

the yoke 48 has been disconnected then movement of the bar will cause the pin 47' of the other yoke 47 to ride up the inclined side of the notch 49 so that the pin will ride on the upper edge of the actuating bar 46. As the actuating bar 46 continues to move to open the other doors to their completely opened position, the notch 49 from which the pin 47' has been disengaged, will, of course, move to the right (Figure 8). It is noted, however, that the distance between the notch 49 and the pin 50 of the yoke 48 is such that when the door is closed and left closed and the actuating bar 46 has moved to entirely open the other doors, the notch 49 will not pass beneath the pin 50 which is in a raised position, as will be explained later. In other words, as is clearly shown in Figure 1 with one of the doors 11 closed while the other door is entirely opened, the notch 49 which is normally engaged by the pin 47' of the yoke 47 does not move into vertical alignment with the pin 50 of the yoke 48 because the travel of the bar 46 is not sufficiently great to move said notch into alignment with said pin. In this way there is no danger of the pin 50 of the yoke 48 ever engaging the notch 49 which is normally engaged by the pin of the other yoke 47. Similarly, if the door has been moved to an open position and it is desired to leave said door in such position while the other doors are being moved to a closed position, it is only necessary to disengage the yoke 47 from its notch 49. Then when the actuating bar 46 is moved to the left (Figures 1 and 8), the notch 49 will, of course, move from beneath the raised yoke 47 and the pin 50 of the other yoke 48 will ride up the inclined side of its notch to ride on the upper edge of the actuating bar 46. The movement of the actuating bar 46 which is necessary to completely close the other doors is not sufficient to move the notch 51 into vertical alignment with the pin 47' of the raised yoke 47. This location of the notches 49 and 51 prevents any danger of the mechanism ever fouling due to the engagement of the pin of one of the yokes with the notch of the other yoke.

For closing the elongated slot 12 through which the extension 11' travels in the opening and closing of the door, an elongated slot cover plate 52 is provided. This cover plate has a width substantially wider than the slot 12 and is suitably secured to the extension 11' whereby it will travel therewith. The cover plate slides on the bottom 25 of the casing and is held in close engagement therewith by angular guide members 54 which engage over the edges of said plate (Figure 8). It is obvious when the door is in a closed position the plate 52 on one side of said extension will close said slot, whereby the occupant of the cell cannot gain access to the casing 32 wherein the operating mechanism is mounted. When the door moves to an open position the plates 52 on the other side of the extension 11' will, of course, move into position over the open end of the slot 12, whereby said slot is covered at all times. For imparting motion to the actuating bar 46 whereby said bar is moved longitudinally within the casing 32 to open or close the doors, a worm 55 is provided. This worm is mounted in the end of the casing 32 adjacent the control compartment 34, and as clearly shown in Figures 2 and 3 this worm is rotatably mounted on a shaft 56 which has one end extending through the end wall of the casing 32 and its other end suitably journaled in an upwardly extending bracket 57 which is fastened to the

bottom of the casing over cell 10. The worm is shown as having a helical groove 58 of varying pitch from one end to the other and is connected to the door actuating bar 46 and by means of a pin 60 extending laterally from the end of the bar 46. The pin is secured within a roller bearing 59 secured to the bar 46, whereby rotation of the pin within the groove is possible which reduces friction. The pin 60, being engaged in the groove 58, it is obvious that when the worm 55 is rotated the bar 46 will be moved longitudinally as said rotating pin travels in the helical groove 58, whereby the actuating bar 46 is moved longitudinally within the casing.

For guiding the actuating or propelling bar 46 in its longitudinal movement the pin 60 is extended outwardly from the bar on the side opposite the roller 59. The outer end of this pin carries a small roller 61 which rides on the inner surface of the vertical side of a channel bar 62 which is located between the end wall of the casing and the bracket 57. A vertically disposed enlarged roller 63 is also journaled on this outer end of the pin 60 and serves to ride in the groove formed by the inwardly extending flanges of the channel bar. Thus it will be seen that the engagement of the rollers 61 and 63 in the channel bar will serve to guide the end of the propelling bar 46 in its longitudinal movement. These rollers also serve to hold the rotating pin 60 positively within the helical groove 58, whereby there is no danger of said pin disengaging from said groove. To further guide the end of the propelling bar 46 and to prevent its vertical displacement a bracket 64 extends upwardly from the end of said bar and the upper end of this bracket is forked so as to permit a guide rail 65 which has one end secured to the end wall of the casing 32 and its other end secured to the bracket 57, to pass therebetween. A roller 66 is journaled at the upper forked end of the bracket 64, and as clearly shown in Figure 2, this roller is arranged to ride on the upper edge of the guide rail 65. A similar roller 67 is mounted in the bracket 64 directly below the guide rail 65 and has its periphery riding on the under side of said rail. It will be obvious that the rollers 66 and 67 serve to positively prevent vertical displacement of the end of the propelling bar 46 during the longitudinal movement of the same.

To impart rotation to the worm 55 so that the propelling bar 46 is moved longitudinally to open or close the doors 11 of the various jail cells, the extended end of the worm shaft 56 is provided with a gear 68 which is located in the control compartment adjacent the inner wall of said compartment 34. The gear 68 is connected by means of a chain 69 with a gear 70 which is mounted on a rotatable shaft 71 which is journaled in the lower end of the control compartment 34. The shaft 71 is suitably supported in a bracket 72, and said shaft extends outwardly toward the front portion of the compartment 34. This outer end of the shaft 71 has a suitable hand wheel 73 secured thereto. A handle 74 is pivoted at a point on the periphery of said hand wheel and this handle is arranged to be swung whereby it will lie at substantially a right angle to the face of the hand wheel 73. When swung to such position, it will be obvious that the operator may grasp the handle 74 and rotate the hand wheel whereby the gear 70 on the shaft 71 is rotated. Rotation of the gear 70 will impart a rotation to the gear 68 through the medium of the driving chain 69. It is noted that when the handle 75

74 on the hand wheel is swung to its operating position said handle would strike the door 34' of the control compartment, if such door were closed. Thus it will be seen that the door to the control compartment cannot be closed until such time as the handle 74 has been swung upwardly out of the way as clearly shown in Figure 2. In this way the handle acts as an indicator to the operator, whereby he cannot close the door to the control compartment unless the handle is swung up.

From the above it will be seen that the locking bar 31 is actuated to operate the various latch bars of the cell doors by merely swinging the elongated lever 35. The doors are moved to an open or closed position by rotating the hand wheel 73 whereby the worm 55 is rotated to impart a longitudinal movement to the propelling bar 46. It is pointed out that the helical groove 58 in the worm 55 is such that three or more complete rotations of the hand wheel 73 will cause the roller 59 in the end of the propelling bar 46 to travel from end of said groove to the other. Thus three or more complete revolutions of the hand wheel 73 will move the doors from either a completely closed position to a completed opened position or vice versa. The disposition of the elongated hand lever 35 together with its particular pivot 36 permits the lower end of the lever to be swung only a short distance in order to move the locking bar 31 a sufficient distance to lock or unlock the latch bars from the doors. Thus a minimum amount of effort on the part of the operator is necessary to actuate the doors and locks.

35 For providing a co-action between the operating element for the locking bar 31 and the propelling bar 46, whereby the propelling bar 46 cannot be actuated until the latch bar 16 is released, and also whereby the latch bar cannot be actuated while the doors are in motion, a grooved control wheel 75 is provided. The wheel 75 is suitably journaled on a shaft 76 which is mounted within the control compartment above and to one side of the hand wheel shaft 71. The wheel is provided with a peripheral groove 77 and the rear face of said wheel is secured to an enlarged gear 78 which is also rotatable on the shaft 76. The enlarged gear is in constant engagement with a pinion 79 which is fastened to the hand wheel shaft 71. It will be seen that when the hand wheel 73 is rotated the grooved wheel 75 will also be rotated through the medium of the pinion 79 and gear 78. The ratio of the pinion and gear is such that when the hand wheel 55 has rotated to completely open or close the doors, the grooved wheel 75 has made one complete revolution.

The location of the wheel 75 is such that its periphery is in close proximity to one side of the hand lever 35. This lever is provided with a laterally extending pin 80 which is arranged to ride within the peripheral groove 77 of the wheel 75. It is noted, however, that the pin engages in said peripheral groove only when the lever has been swung to unlock the doors, that is when the lower end of said lever is inwardly within the control compartment 34. Assuming that the jail doors are completely closed and the parts are in the position shown in Figures 2 and 4, it will be seen that the hand lever 35 has been swung to lock said doors. At this time the pin 80 on said hand lever has entered a transverse groove 81 which connects the outer face of the grooved wheel 75 with the peripheral groove 77 whereby the lever 35 may be swung when the groove 81

is in alignment with the pin 80. Now assuming that it is desired to operate the doors, it will be seen that the lever 35 is first swung so as to release the latch bar 16, as has been explained. This swinging of the lever 35 will cause the pin 80 to enter the peripheral groove 77 of the wheel 75. Thus the hand wheel 73 is rotated which imparts a rotation to the grooved wheel 75. As the hand wheel rotates it, of course, opens the jail doors 11. So long as the hand wheel 73 is rotated and until such time as the door has moved to its completely opened or closed position, the pin 80 on the lever 35 is travelling within the peripheral groove 77 in the wheel 75. During this time it is obvious that the lever 35 cannot be 15 swung because said pin 80 is engaging in the peripheral groove. When the doors have been swung to their completely open or closed position, the wheel 75 has made one complete revolution whereby the transverse slot or groove 81 20 is again in alignment with the pin 80 on the lever 35. At such time the lever 35 may be again swung whereby the pin 80 will again enter the groove 81. So long as said pin is within this transverse groove it is obvious that the hand 25 wheel 73 cannot be rotated because the pin engaging in said transverse groove 81 will prevent rotation of grooved wheel 75. Therefore it will be seen that the locking mechanism cannot be operated except when the doors are in their 30 completely opened or completely closed position. While the doors are in motion the operating lever 35 for actuating the latch bar 16 cannot be moved and therefore there is no danger of actuating the latch member while the doors are in motion. 35

Similarly, when the doors are in a locked position, the hand wheel 73 cannot be rotated whereby it is impossible to operate the actuating bar 46 while the latch bars 16 are in a locked position. 40 From the above, it will be seen that the propelling bar 46 controls the opening and closing of the doors through the medium of the yokes 47 and 48 which engage in the notches 49 and 51 respectively in the upper edge of said propelling bar. It will further be seen that the latch bar of each 45 door is controlled through the operation of the locking bar 31 which is connected to the actuating member 26 of each latch bar through the medium of the yoke 49 and pin 41 which engages in the notch 42 in the upper edge of said locking bar. 50 As has been pointed out, so long as the yokes 47 and 48 are engaged with the propelling bar 46 and the yokes 49 are engaged with the locking bar 31, then it will be seen that an actuation of the two bars 46 and 31 will operate all of the doors 55 and locks of same, in a particular row over which the bars 46 and 31 may extend. When it is desired to cut out or prevent the operation of any one or more particular doors, then it will be seen that it is necessary not only to disconnect the 60 yoke 49 of the actuating member 26 of the particular latch bar associated with that door, but it is also necessary to disconnect the yoke 48 from the notch 51 in the actuating bar 46, whereby that particular door will remain in a locked 65 and closed position, while the other doors in the row may be opened and locked.

For disconnecting the yoke 49 of a particular door from the locking bar 31, and at the same time disengaging the yoke 48 from connection 70 with the propelling bar 46, a pivoted release member 90 (Figures 7, 8 and 9) is provided. This release member has a general triangular shape and has its apex secured on a transverse shaft 91 which extends completely across the casing 32 75

and is located in a plane above the propelling bar 46 and locking bar 31. The release member 90 is fastened on this shaft between the rear side of the propelling bar 46 and the forward side of the locking bar 31, as is clearly shown in Figure 7. The release member is provided with a curved shoe 92 which extends forwardly from one side of said member. The location of this shoe is such that the pin 50 which connects the outer end 10 of the yoke 48 and which extends outwardly from the inner side of said yoke 48 may rest upon the upper end of this curved shoe. Therefore when the release member 90 is swung upwardly the shoe, engaging beneath the extended pin 50 of 15 the yoke 48 will serve to raise the outer end of said yoke which will cause the pin 50 between the yoke arms to rise out of the notch 51 in the propelling bar 46. Therefore, when the release member 90 is swung upwardly to raise the outer 20 end of said yoke, it will be obvious that when the propelling bar 46 is moved longitudinally to open the doors of the various cells, the door to which the yoke 48 is connected will not be moved from its closed position because of the disconnection of the pin 50 with the notch 51. In order 25 to permit the release member 90 to disengage the pin 41 of the yoke 40 from its notch 42 in the locking bar 31, said release member is provided with a horizontally extending slot 93 through 30 which one extended end of the pin 42 passes. As clearly shown in Figure 7 it will be seen that this extended end of the pin 41 is constantly in engagement with the horizontal slot 93. Therefore when the release member is swung upwardly so 35 that the shoe 92 will raise the yoke 48, as has been explained, the swinging of said release member will at the same time cause the outer end of the yoke 40 to swing upwardly, whereby its pin 41 will disengage the notch 42 in the locking bar. 40 Therefore it will be seen that the single release member not only disengages the yoke 48 to cut out the opening of the door to which said yoke is attached, but it also raises the yoke 40 from engagement with the locking bar 31, whereby the 45 latch bar, 16 of that door will not be operated and such door will remain in a closed locked position. To positively assure that the latch bar 16 of the door or doors cut out, will remain in a lowered locked position while other doors in the row are 50 being operated and locked, the release member 90 is provided with an arcuate surface 94 at its underside. The pin 28 by which the upper end of the latch bar 16 is pivoted to its actuating member 26 (Figures 11 and 14), is extended outwardly so that 55 this extended end of the pin is in the path of the curved underside 94 of said release member. It will be obvious that when the release member 90 is in a normal position with the yokes 48 and 40 engaging their respective bars, the latch bar 16 may be raised by its actuating member 26 and the extended end of the pin 28 will pass upwardly 60 into a cut out portion 95 formed in the release member 90. However when the latch bar 16 is in a lowered locked position and it is desired to release the yokes 40 and 48 from their respective bars 31 and 46, then the swinging of said release member not only disengages the pins 42 and 50 of the yokes 40 and 48 from their respective notches in the propelling and locking bar, but the 65 curved underside 94 of said release bar 90 will ride up over the top of the extended end of the pin 28. Thus so long as the release member is in a position holding the yokes 40 and 48 disconnected from the locking and propelling bar, the 70 curved underside 94 of said release member is 75

above the extended end of the pin 28, whereby it is impossible to raise the latch bar 16 until such time as the release member 90 has been returned to its original position.

For swinging the release member 90 so as to disconnect the yokes as above explained, an actuating arm 96 is fastened on the transverse shaft 91 and extends upwardly therefrom as is clearly shown in Figure 5. This actuating arm may be secured at any point transversely of the shaft and has its upper end connected with one end of a pull rod 97 which extends from said upper end longitudinally through the casing 32 and outwardly through the end wall of said casing into the control compartment 34 (Figure 2). 15 This end of the pull rod which extends into the control compartment is secured to the upper end of a pivoted bell crank member 98 which may have a general triangular shape. The bell crank is suitably pivoted to the inner wall of the control compartment 34. An operating rod 99 having a suitable handle at its lower end is secured to the other end of the bell crank lever, whereby when said operating rod is pulled downwardly the pull rod 97 will be moved longitudinally 25 within the casing in a direction to the left (Figures 2 and 5). When the pull rod is moved in this direction it will be obvious that the actuating arm 96 is swung whereby the transverse shaft 91 is rotated. Rotation of the shaft 91 30 will swing the release member to disengage the yokes 40 and 48 from their respective bars whereby that particular door is cut out. It is pointed out that a similar arrangement of pull rods is provided for the other doors. By mounting the actuating arm 96 at any point along the transverse shaft, it is noted that the arm 96 of each door may be mounted in different vertical planes, whereby the pull rods extending from such actuating arms will all be in a different vertical plane 40 within the casing 32. By providing such an arrangement it is not necessary to bend the pull rod around the actuating arm of another door as is the case in many of the devices of this nature now in general use. By eliminating bending of the pull rod it is obvious that a more direct pull may be obtained and also a longer life is given the pull rod with more efficient operation throughout the life thereof. In order to properly distribute the pull rods vertically in casing 32 to avoid the necessity of bending pull rods, and at the same time maintain uniform movement of pull rods 97, the relative vertical length of release member 90 and arm 96 may be uniformly increased or decreased on the various 50 transverse shafts 91. If desired the handle at the lower end of the operating rod 99 (Fig. 2) may be made larger than the pull rod so that said handle may be engaged in a notch holder 100 or 101 depending on the position of said rod. In other words when the release member is in a normal position as shown in Figure 5, the handle of the operating rod 99 is engaged in the notch of a bracket 100. When the rod 99 is pulled downwardly to impart a movement to 55 the pull rod 97 to actuate the release member, then the handle of the pull rod is engaged in the notch of the lower holder 101. In this way a positive means for holding the pull rods in the positions to which they are moved is provided and there is no danger of the release member 90 swinging from one position to the other without a positive actuation of the pull rod.

From the above it will be seen that a simple, compact and inexpensive operating mechanism 75

for actuating the doors and locks of a plurality of jail cells is provided. The master propelling bar 46 controls the opening and closing of the doors, while the master locking bar 31 controls the actuation of the latch bar 16. A single release member 90 is provided for each door and this release member not only serves to disconnect the particular door from the master propelling bar 46, but at the same time it disconnects the latch bar of said door from the master locking bar 31, whereby the door may be neither unlocked or opened. The manual control for actuating the locking bar, the propelling bar and the release member are all mounted in a single control compartment which is located at one end of the row of cells. Ready access is had thereto and means is provided whereby the propelling bar cannot be actuated until the doors are unlocked, said means also serving to prevent operation of the locking bar 31 while the propelling bar is actuating and the doors are in motion. The device is made simple and may be operated by the most inexperienced operator. For indicating to the operator who is located at the control compartment, as to whether or not all the doors in the row of cells are operating correctly, an indicating means is provided for each door. This indicating means is clearly shown in Figures 6 and 7 and includes an elongated slot bar 102 which has one end secured to the end of the extension 11' of the door. The other end of this bar is inclined downwardly to the bottom 25 of the casing. An elongated slot 103 is provided in the bar 102 and extends substantially throughout the length thereof. A pin 104 engages in this slot 103, and the pin is located on the outer end of a horizontally disposed arm 105. The other end of the arm is fastened on a rotatable shaft 106 which has one end journaled in a bearing 107 and its other end journaled in the rear wall of the casing 32. It is noted that the rotatable shaft 106 extends below the propelling bar 46 and locking bar 31. It is obvious that due to the inclination of the bar 102, that as the door 11 is actuated or moved to its open position the bar 102 is also moved in the same direction. The pin 104 on the arm 105 riding within the slot 103 in the bar will cause the arm 105 to swing upwardly because of the inclination of the slot 103. As the arm 105 swings upwardly it will rotate the shaft 106. Rotation of the shaft will swing an elongated arm 107 which is fastened on said shaft and extends upwardly therefrom. This elongated arm has an indicator rod 108 fastened to its upper end and the rod 108 extends longitudinally within the casing and outwardly through the end wall of said casing into the control compartment 34. The swinging of the arm 107 will, of course, impart a longitudinal movement to the indicator rod 108 and by numbering the rod at its front end it will be obvious that the operator who is standing at the control compartment can watch the movement of said rods 108 and thereby ascertain just what doors are moving and if one happens to be inoperative, he can immediately tell which one. For guiding the indicating bar 102 in its longitudinal travel the lower end of said bar is provided with a laterally extending pin 109 which engages in a horizontal slot 110 formed in an angular supporting member 111 which is secured to the bottom 25 of the casing. By observing Figure 7 it will be seen that as the door 11 is moved to an open position and the bar 102 is moved therewith, the engage-

ment of the pin 109 within the slot 110 will serve to guide the lower end of the bar 102 in its longitudinal travel. It is obvious that after the door has moved to its completely open position the arm 105 will have been swung to have moved the indicating rod 108 a particular distance which denotes that the door is now open. As the door is returned to its closed position it will be seen that since the pin 104 is in constant engagement with the slot in the bar 102, the arm 105 will be returned to its original position and during such return will, of course, move the indicating rod 108. Therefore the operator is informed during the opening, as well as during the closing of the door of the operation of said door. By determining the length of travel of the rod 108 within the control compartment 34, the operator can ascertain the exact position of the door as it is moving. The rotating shaft 106 permits the location of arm 107 at any point transversely of the casing thereon, so as to permit the proper distribution of indicator rods 108 in the casing. By proper proportioning of the lengths of the arms 105 and 107, the movements of indicator rods 108 may be made uniform.

In operation, assuming the parts to be in the position shown in the drawings with the doors 11 in a closed and locked position, it is obvious that the hand wheel 73 which controls the operation of the propelling bar 46 cannot be revolved until the hand lever 35 is swung to actuate the locking bar 31 to unlock the doors by raising the latch bar 16. This is true because the pin 80 on said hand lever is in engagement with the transverse groove or slot 81 in the grooved wheel 75.

The hand lever 35 is swung which action raises the latch bars 16 of all the doors 11, whereby the doors are unlocked. Of course, if the release member 90 of any particular door has been swung by moving the pull rod 97 of said release member, then the connecting yoke 40 of the actuating member 26 for the latch bar of that door is disengaged from the locking bar 31, whereby that door remains in a locked closed position. Therefore, it will be seen that anyone or a number of the doors can be selectively cut out.

After the locking bar 31 has been actuated by the swinging of the lever 35, the hand wheel 73 may then be rotated because the pin 80 on said hand wheel has moved into the peripheral groove 77 of the wheel 75 as has been explained. Rotation of the hand wheel 73 imparts a movement to the propelling bar 46 which slides the doors 11 to their open position. If any of the release members 90 of the doors have been swung to prevent unlocking of a particular door, said release member has also disconnected the yoke 40 of that door from the bar 46, whereby such door remains inactive.

While the doors have been slid to their completely open position, the grooved wheel 75 has made one complete revolution, so that the transverse slot 81 is again aligned with the pin 80 of the hand lever 35. It is noted that while the pin 80 is travelling in the peripheral groove 77, which is while the doors are in motion, the lever 35 cannot be swung to actuate the locking bar 31, thus avoiding fouling or damaging the locking mechanism by trying to operate lever 35 while doors are in motion.

As soon as the doors have moved to their completely open position, the lever 35 is again swung so that the pin 80 engages in the transverse slot 81. This return swinging of the lever actuates

the locking bar 31 in an opposite direction to lower the latch bar 16, whereby the leg 16' of said bar engages the notches 18' and 21' in the door frame supporting members 20 and 20' to lock the 5 doors in an open position.

It is noted that when the doors 11 are in a closed position, the extended end of the pin 50 of the yoke 48 of each door is located immediately over the curved shoe 92 of the release member 90. 10 Thus, if said release member is swung before the doors are opened, the yoke 48 is disconnected from the bar 46. However, assuming the door is slid to an open position, then the length of travel of said door as it moves from a closed to an open 15 position causes the extended end of the pin 47' of the yoke 47 to move into alignment with the shoe, as is clearly shown in Figure 1.

Therefore, when the door is closed the pin 50 of the yoke 48 is located over the curved shoe 92 20 of the release member 90. When the door is completely open, the pin 47' of the yoke 47 is located over said shoe. Thus, after the doors have been slid to an open position and locked, and it is desired to leave one of said doors in 25 an open locked position, while the others are being closed, then it is only necessary to operate the release member 90 of the door to remain open. Swinging of the release member will cause the shoe 92 to raise the outer end of the yoke 30 47 from its notch 49 in the propelling bar 46. At the same time, the release member will disengage the yoke 40 from the locking bar 31. Thus any particular door, or any desired number 35 of doors may be locked in an open position, while the remainder of said doors are moved to their original closed position. It is noted that the release member 90 cannot be actuated to cut out any particular door unless such door is in a locked open or locked closed position because if the 40 latch bar 16 is in a raised or unlocked position then the front face 94' (Fig. 9) of release member 90 would strike pin 28, thus avoiding the possibility of shoes 92 being raised except when pins for lifting yokes are immediately over them.

45 It is pointed out that the entire mechanism has been constructed with a view to simplicity so that the most inexperienced operator can control the doors. The controls are so arranged that the propelling bar cannot be actuated until the locking bar has been operated. Neither can the locking bar be actuated while the doors are in motion. 50 This positively eliminates any danger of fouling the mechanism, at any time.

Any single one or any desired number of the 55 doors may be locked in a closed position while the remainder of the doors are operated in the usual manner. Similarly, any one or any desired number of the doors can be locked in an open position while the remainder are returned to a 60 closed position. Thus, every possible condition is taken care of for one of the doors can be in an opened, locked position, or any desired number may be in such position while the other doors are operated from opened to closed. Any door 65 may be selectively cut out from the system by a single release member for that door which is manually operated from a single point. Further, a simple, indicating means is provided for each door, whereby the operator is advised of the movement of each particular door during actuation 70 of the mechanism.

What I claim and desire to secure by Letters Patent is:

75 1. An operating mechanism for a plurality of doors including, a common propelling bar, means

for detachably connecting each door with the bar whereby said doors are opened and closed by the movement of said bar, a common locking bar, latch means for each door, means for detachably connecting each latch means with said locking bar, and a single means for each door 5 for actuating the connecting means between the door and propelling bar and also for actuating the connecting means between the latch means of said door and the locking bar, whereby the door is disconnected from the propelling bar and the latch means thereof is disconnected from the locking bar.

2. An operating mechanism for a plurality of doors including, a common propelling bar, means 15 for detachably connecting each door with the bar whereby said doors are opened and closed by the movement of said bar, a common locking bar, latch means for each door, means for detachably connecting each latch means with said locking bar, a single means for each door for actuating the connecting means between the door and propelling bar and also for actuating the connecting means between the latch means of said door and the locking bar, whereby the door is disconnected 20 from the propelling bar and the latch means thereof is disconnected from the locking bar, and means for preventing actuation of the locking bar while the propelling bar is in an intermediate position and the doors connected therewith are 25 not in a completely open or closed position.

3. An operating mechanism for a plurality of doors including, a common propelling bar, means 35 for detachably connecting each door with the bar whereby said doors are opened and closed by the movement of said bar, a common locking bar, latch means for each door, means for detachably connecting each latch means with said locking bar, a single means for each door for actuating the connecting means between the door and propelling bar and also for actuating the connecting means between the latch means of said door and the locking bar, whereby the door is disconnected from the propelling bar and the latch means thereof is disconnected from the locking bar, and means for indicating the 40 position of each door when the propelling bar is operated.

4. An operating mechanism for a plurality of doors including, a common propelling bar, means 45 for detachably connecting each door with the bar whereby said doors are opened and closed by the movement of said bar, a common locking bar, latch means for each door, means for detachably connecting each latch means with said locking bar, a single means for each door for 50 actuating the connecting means between the door and propelling bar and also for actuating the connecting means between the latch means of said door and the locking bar, whereby the door is disconnected from the propelling bar and the latch means thereof is disconnected from the locking bar, means for indicating the position 55 of each door when the propelling bar is operated, and means for preventing actuation of the locking bar while the propelling bar is in an intermediate position and the doors connected therewith are 60 not in a completely open or closed position.

5. An operating mechanism for a plurality of 70 doors including, a common propelling bar, swinging means for detachably connecting each door with said bar whereby actuation of the bar will impart motion to said doors, a common locking bar, a latch for each door, swinging means for 75

5 detachably connecting each latch with said locking bar whereby actuation of the bar will lock or unlock the door, and an individual means for engaging the connecting means between the propelling bar and each door and also for engaging the connecting means between the locking bar and the latch of said door to swing the same, whereby upon actuation of said individual means the door is disconnected from the propelling bar 10 and its latch is disconnected from the locking bar.

6. An operating mechanism for a plurality of doors including, a common movable propelling bar, a pivoted yoke secured to each door for engaging the propelling bar to connect said door to the bar, a common locking bar, a latch for each door, a pivoted yoke connected with each latch for engaging the locking bar to connect the locking bar and latch, and a single means above each door 20 for engaging the yokes associated with that door to swing the same and disconnect said door from the propelling bar and to disconnect the latch of said door from the locking bar.

7. An operating mechanism for a plurality of 25 doors including, a common movable propelling bar, a pivoted yoke secured to each door for engaging the propelling bar to connect said door to the bar, a common locking bar, a latch for each door, a pivoted yoke connected with each latch 30 for engaging the locking bar to connect the locking bar and latch, and a swinging member for each door adapted to engage the yokes to swing the same, whereby the door is disconnected from the propelling bar and the latch is disconnected 35 from the locking bar.

8. An operating mechanism for a plurality of doors including, a common movable propelling bar, a pivoted yoke secured to each door for engaging the propelling bar to connect said door to the bar, a common locking bar, a latch for each door, a pivoted yoke connected with each latch for engaging the locking bar to connect the locking bar and latch, a single means above each door for engaging the yokes associated with that door to swing the same and disconnect said door from the propelling bar and to disconnect the latch of said door from the locking bar, and means for indicating the position of each door when the propelling bar is moved.

50 9. An operating mechanism for a plurality of doors including, a common movable propelling bar, a pivoted yoke secured to each door for engaging the propelling bar to connect said door to the bar, a common locking bar, a latch for each door, a pivoted yoke connected with each latch for engaging the locking bar to connect the locking bar and latch, a single means above each door for engaging the yokes associated with that door to swing the same and disconnect said door from 55 the propelling bar and to disconnect the latch of said door from the locking bar, and means for preventing actuation of the locking bar while the propelling bar is in an intermediate position and the doors connected therewith are not in a completely open or closed position.

10. An operating mechanism for a plurality of doors including, a common movable propelling bar, a pivoted yoke secured to each door for engaging the propelling bar to connect said door to the bar, a common locking bar, a latch for each door, a pivoted yoke connected with each latch for engaging the locking bar to connect the locking bar and latch, a swinging member for each door adapted to engage the yokes to swing the same, whereby the door is disconnected from

the propelling bar and the latch is disconnected from the locking bar, and means for preventing actuation of the locking bar while the propelling bar is in an intermediate position and the doors connected therewith are not in a completely 5 open or closed position.

11. An operating mechanism for a plurality of doors including, a common movable propelling bar, a pivoted yoke secured to each door for engaging the propelling bar to connect said door to the bar, a common locking bar, a latch for each door, a pivoted yoke connected with each latch for engaging the locking bar to connect the locking bar and latch, a swinging member for each door adapted to engage the yokes to swing 10 the same, whereby the door is disconnected from the propelling bar and the latch is disconnected from the locking bar, means for preventing actuation of the locking bar while the propelling bar is in an intermediate position and the doors 15 connected therewith are not in a completely open or closed position, and means for indicating the position of each door when the propelling bar is moved.

12. An operating mechanism for a plurality of 25 doors including, a common propelling bar, a pivoted yoke secured to each door for engaging the propelling bar to connect said door to the bar, a rotatable worm having a driving connection with the bar to move said bar when the worm is rotated, manually operated means for rotating said worm, a common locking bar, a latch for each door, a pivoted yoke connected with each latch for engaging the locking bar to connect said 30 latch with the bar, manually operated means for moving the locking bar to actuate all of the latches connected therewith, and means for preventing operation of the propelling bar when the locking bar is in a position holding the latches in a locked position and also for preventing movement of the locking bar when the propelling bar 35 is in an intermediate position.

13. An operating mechanism for a plurality of doors including, a common propelling bar, a pivoted yoke secured to each door for engaging the 45 propelling bar to connect said door to the bar, a rotatable worm having a driving connection with the bar to move said bar when the worm is rotated, manually operated means for rotating said worm, a common locking bar, a latch bar for each 50 door, a pivoted yoke connected with each latch for engaging the locking bar to connect said latch with the bar, manually operated means for moving the locking bar to actuate all of the latches connected therewith, a single means 55 above each door for engaging the yokes associated with that door to simultaneously swing the same, whereby such door is disconnected from the propelling bar and the latch of said door is disconnected from the locking bar, and means for preventing operation of the propelling bar when the locking bar is in a position holding the latches in a locked position and also for preventing movement of the locking bar when the propelling bar is in an intermediate position.

14. An operating mechanism for a plurality of doors including, a common propelling bar, means for detachably connecting each door with the bar whereby said doors are opened and closed by the movement of said bar, a common locking bar, 70 latch means for each door, means for detachably connecting each latch means with said locking bar, a transverse shaft extending above each door and disposed transversely within the casing, a single swinging release means on each shaft for 75

engaging the connecting means between the door therebelow and the propelling bar and also for engaging the connecting means between the latch means of said door and the locking bar 5 whereby when the release means is swung the door and its latch are disconnected, an actuating member secured on each shaft and extending upwardly therefrom, and a pull rod connected with each actuating member for swinging the 10 release member, the rods of all of the release members terminating at a common point so as to be readily accessible to the operator and also being mounted in various vertical and horizontal

planes whereby the necessity of bending the rods is eliminated.

15. An operating mechanism for a plurality of doors including, a common propelling bar adapted to be detachably connected to each door, a 5 latch for each door, a common locking bar adapted to be detachably connected to each latch, and a single swinging member located above each door for disconnecting the door therebelow from the propelling bar and for simultaneously disconnecting the latch of said door from the locking bar. 10

JAMES A. YOUNGBLOOD.
